UNITED STATES PATENT OFFICE.

EDWIN H. STEEDMAN, OF ST. LOUIS, MISSOURI, ASSIGNOR TO CURTIS & CO. MFG. CO.,
OF WELLSTON, MISSOURI, A CORPORATION OF MISSOURI.

OVERHEAD CRANE.

1,397,558.

Specification of Letters Patent.

Patented Nov. 22, 1921.

Application filed June 11, 1921. Serial No. 476,962.

To all whom it may concern:

Be it known that I, EDWIN H. STEEDMAN, a citizen of the United States, residing at St. Louis, Missouri, have invented a certain 5 new and useful Improvement in Overhead Cranes, of which the following is a full, clear, and exact description, such as will enable others skilled in the art to which it appertains to make and use the same.

10 This invention relates to overhead cranes, and particularly small cranes of the kind that are intended to be moved manually by pressure applied to the object suspended from the crane or by an operating shaft 15 geared to two of the wheels of the crane.

The main object of my invention is to provide a strong, lightweight crane of the type referred to that can be manufactured at a low cost.

20 To this end I have devised a crane that comprises two end frames, each of which consists of a fabricated structure composed of a number of pressed metal members or commercially rolled members or a rolled 25 member and a number of pressed members, and a tie member that joins said end frames together and also serves as a track for a trolley that can be moved at right angles to the path of travel of the crane.

30 Figure 1 of the drawings is a perspective view of a crane constructed in accordance with my invention.

Figs. 2 and 3 are a top plan view and a side elevation of one of the end frames of 35 the crane shown in Fig. 1.

Figs. 4 and 5 are a top plan view and a side elevation, respectively, of an end frame of slightly different construction; and

40 Figs. 6, 7 and 8 are top plan views, illustrating other ways of constructing the end frames of the crane.

Referring to Figs. 1 to 3 of the drawings, A designates the end frames of my improved crane, and B designates a tie member that 45 joins said end frames together and also serves as a track for a trolley B' from which the object carried by the crane is suspended. Each of the end frames A is made up of a number of parts riveted or otherwise connected together, thus making the crane 50 lighter and less expensive to manufacture

than a crane provided with end frames consisting of heavy castings, such as are generally used to form the end frames of small overhead cranes. In the form of my invention shown in Figs. 1, 2 and 3, each end frame A is composed of two pressed metal members 1 of channel shape in cross section arranged with their vertical webs back to back and their flanges 2 projecting outwardly. The members 1 extend the entire length of the end frame and their end portions are separated or spaced apart, as shown in Fig. 2, so as to form jaws for the wheels C of the crane. Preferably, each of the members 1 is provided with a relatively deep intermediate portion and shallow end portions, as shown in Fig. 3, thus forming an end frame having an intermediate portion of substantially I shape in vertical cross section equipped at its ends with flanged wheel jaws. The members 1 are preferably joined together by top and bottom plates 3 arranged in overlapping relation with the flanges 2 of said members and secured to said flanges 75 by rivets 4 or in any other preferred manner, the plates 3 extending longitudinally of the end frame and terminating just beyond the points where the end portions of said members 1 start to flare outwardly to form the 80 wheel jaws of the end frame. In some instances inclined braces D are connected to the end frames and to the tie member B, as shown in Fig. 1, and when the crane is constructed in this manner, it is preferable to 85 provide the inner members 1 of the end frames with integral brackets 5 to which the outer ends of the braces D are connected, said brackets 5 being formed by slitting the vertical web of the inner member of each 90 end frame and bending said slitted portions laterally, as shown in Figs. 2 and 3.

An overhead crane of the construction above described is exceptionally strong and rigid and it is considerably lighter and less 95 expensive to manufacture than a crane equipped with end frames composed of heavy castings.

While I prefer to arrange horizontally-disposed top and bottom plates in overlapping relation with the flanges of the members 1 constituting each end frame to secure

said members together, it is not essential that the end frame be provided with top and bottom plates, for if desired, each end frame can consist simply of two pressed metal, 5 channel-shaped members arranged back to back with their vertical webs connected together by rivets 3^a, as shown in Figs. 4 and 5, the end portions of said members being spread so as to form jaws for the wheels of 10 the crane.

In Fig. 6 I have illustrated another form 15 of my invention in which each end frame is composed of one pressed metal, channel-shaped member E that extends the entire length of the end frame, and jaw members F of channel shape in cross section arranged at the opposite ends of said member E and securely connected to same, the end portions 20 of the member E and the jaw members F being bent laterally so as to form jaws for the wheels. When the end frame is constructed in this manner it is preferable to secure the vertical webs of the jaw members F to the vertical web of the member E by 25 rivets 8^b and also arrange top and bottom plates 7 in overlapping relation with the flanges of the member E and the jaw members F and secure said plates to said flanges by rivets or other fastening devices 8.

In Fig. 7 I have illustrated an end frame 30 embodying my invention which is composed of an I-beam G or other suitable commercially rolled member having pressed metal jaw members F' arranged at the opposite ends of same and secured to the vertical web thereof by rivets or other suitable fastening devices 9, the member G terminating at the points where the jaws F' start to flare outwardly.

The end frame shown in Fig. 8 is substantially 40 the same as the end frame illustrated in Fig. 6, in that it is composed of a single pressed metal member E having jaw members F arranged at the ends of same, but it 45 is not equipped with top and bottom plates like the plates 7 of the end frame shown in Fig. 6.

Having thus described my invention, what I claim and desire to secure by Letters Patent is:

1. An overhead crane composed of two end frames, each of which consists of a number of flanged members connected together, and a transversely disposed connecting means for 55 said end frames arranged wholly within the space between same and having its opposite ends directly connected to said end frames.

2. An overhead crane, comprising end frames, each of which consists of a built up 60 structure of flanged members connected together and provided at its ends with laterally flared portions that constitute wheel jaws, and a tie member that joins said end frames together and also serves as a track 65 for the trolley of the crane.

3. A crane, comprising end frames, each of which is composed of a plurality of flanged members combined in such a manner that they form an end frame of substantially I shape in cross section provided at its ends 70 with laterally projecting portions that form the side pieces of wheel jaws, and a connecting means that joins said end frames together.

4. A crane having fabricated end frames, 75 each of which comprises an intermediate portion of substantially I shape in cross section and end portions consisting of wheel jaws whose side pieces are disposed in different vertical planes from the vertical plane in 80 which the web of said intermediate portion lies, and a tie member that joins said end frames together.

5. A crane composed of two end frames joined together, and each consisting of a 85 fabricated structure of flanged shapes combined in such a manner as to form a relatively deep intermediate section having a vertical web and laterally projecting flanges, and spaced wheel jaws at the opposite ends 90 of said intermediate section having side pieces that lie in different vertical planes from the plane of said web.

6. A crane provided with fabricated end frames, each of which comprises a relatively 95 deep intermediate portion provided at its ends with shallow wheel jaws having side pieces that flare outwardly relatively to said intermediate portion.

7. A crane composed of two fabricated end 100 frames, a tie member that joins said end frames together, braces connected to said tie member and end frames, and integral brackets on said end frames formed by slitting and bending the web portions of some of the 105 members that constitute said end frames.

8. A crane having end frames, each of which is composed of two pressed metal members of channel shape in cross section arranged back to back and having their end 110 portions spread apart so as to form wheel jaws.

9. A crane having end frames, each of which is composed of two pressed metal members of channel shape in cross section 115 arranged back to back and having their end portions spread apart so as to form wheel jaws, and top and bottom plates secured to the flanges of said members.

10. A crane having end frames, each of 120 which consists of a pressed metal member of substantially channel shape in cross section whose end portions are bent laterally to form the sides of wheel jaws, and co-operating jaw members secured to the end portions 125 of said member.

11. A crane having end frames, each of which consists of a pressed metal member of substantially channel shape in cross section 130 whose end portions are bent laterally.

to form the sides of wheel jaws, coöperating jaw members secured to the end portions of said member, and top and bottom plates secured to the flanges of said member and jaw members.

12. A crane provided with end frames, each of which consists of a commercially rolled member that constitutes the intermediate portion of the end frame, and laterally

flared jaw members arranged at the ends of 10 said rolled member.

13. A crane having end frames, each of which consists of an I-beam that constitutes the intermediate portion of the end frame, and pressed metal jaw members arranged at 15 the ends of said I-beam and secured to the vertical web of same.

EDWIN H. STEEDMAN.
